ATTORNEY

UNITED STATES PATENT OFFICE.

JOHN D. BURKHART, OF DAYTON, WASHINGTON.

CULTIVATOR.

SPECIFICATION forming part of Letters Patent No. 430,828, dated June 24, 1890.

Application filed September 9, 1889. Serial No. 323,471. (No model.)

To all whom it may concern:

Be it known that I, JOHN D. BURKHART, of Dayton, in the county of Columbia, Washington Territory, have invented a new and 5 useful Improvement in Cultivators, of which the following is a specification.

My invention consists in a new and improved cultivator, which will be hereinafter fully described and claimed.

10 Referring to the accompanying drawings, Figure 1 is a top plan view of my improved cultivator. Fig. 2 is a vertical transverse section on the line 2 2, Fig. 1. Fig. 3 is a detail view of the plow-beam.

15 The same letters of reference indicate corresponding parts in all the figures.

Referring to the several parts by letter, A indicates the front, A' the back, and A² the side pieces of the rectangular frame of my 20 cultivator.

B indicates the tongue, which is secured across the frame, as shown, and upon the rear end of the tongue is secured the spring-seat C, as shown.

25 D indicates the plow or shovels of the cultivator, which are formed at the back with the wide open space D², leaving the long diverging wings D' D'. These plows or shovels are secured to the lower ends of curved beams

30 E, which are curved, as shown in the drawings, and to the upper ends of which are bolted the rear converging ends of connecting-rods F F'. Upon the front bar A of the cultivator-frame are bolted stirrups G, upon

35 which the eyed forward-diverging ends of the connecting-rods F and F' are pivotally mounted. The front upper end of each beam E is formed with a transverse slot E', and the rear ends of the rods F F' have a threaded

40 bolt F² passing through them and through this slot E', by which arrangement the ends of the beams E can be adjusted up or down, and secured by tightening a nut F³ on the end of each bolt F², to cause the plows to run 45 deep or shallow.

The connecting-rods F' are made so much

shorter than the rods F that they will bring the plows to which they are secured in advance of the plows to which the rods F are secured. The plows are arranged alternately, 50 as shown, those with the shorter rods F' in between the plows having the longer rods F, by which construction and arrangement a greater number of these plows with their long wings can be secured in the frame than if it 55 was attempted to place them side by side.

Between the rear ends of the side pieces A² of the frame is journaled a roller H, having short arms H' in line with the plow-beams, the outer ends of these roller-arms being 60 connected by chains I to the plow-beams below them. On this roller is secured a hand-lever J, and it will be seen that by drawing back this lever by the hand the driver can readily and instantly raise all of the plows 65 clear of the ground, and can hold them thus elevated by allowing a spring-catch K on the side of the lever-handle to engage with a rack L.

The axle M is in two parts or sections, the 70 sections being mounted in bearings N on the under side of the side pieces A², and also mounted at their inner ends in a box O. The shaft-sections have on their outer ends the usual iron wheels P.

75 Having thus described my invention, what I claim, and desire to secure by Letters Patent, is—

The improved cultivator, consisting of the tongued frame, the axle and wheels, the plows 80 D, each having lateral wings D' D', their curved beams E, and diverging connecting-rods F F', rigidly attached to said beams, the stirrups G, attached to front of the frame, and each serving as point of attachment for 85 one of the rods of a beam, the roller H, having arms H', chains I, hand locking-lever, and rack L, all as shown and described.

JOHN D. BURKHART.
